(57) **CLAIM**

The ornamental design for a butterfly swaddle, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front, top, right perspective view of a butterfly swaddle in an open position, comprising a swaddle and a blanket inserted into the swaddle.

FIG. 2 is a rear, top, right perspective view thereof.

FIG. 3 is a front elevation view thereof.

FIG. 4 is a rear elevation view thereof.

FIG. 5 is a right side elevation view of the swaddle.

FIG. 6 is a left side elevation view of the swaddle.

FIG. 7 is a top plan view of the butterfly swaddle.

FIG. 8 is a bottom plan view thereof.

FIG. 9 is a front, top, right perspective view showing the butterfly swaddle in an open position on an infant; and, FIG. 10 is a front, top, right perspective view showing the butterfly swaddle in a closed position on an infant.

The broken lines shown in the drawings define the bounds of the claimed design and form no part thereof.

1 Claim, 9 Drawing Sheets
